195,337

MINIATURE ELECTRONIC WELDING HEAD

Meredith M. Nyborg, Camarillo, Calif., assignor to Hughes Aircraft Company, Culver City, Calif., a corporation of Delaware

Filed Oct. 30, 1962, Ser. No. 72,317

Term of patent 14 years

(Cl. D26—1)

FIG. 1.

FIG. 3.

FIG. 2.

FIG. 5.

FIG. 4.

FIGURE 1 is a perspective view of a welding head, showing the new design;
FIG. 2 is a side elevational view;
FIG. 3 is a front elevational view;
FIG. 4 is a top plan view;
FIG. 5 is a back elevational view.

I claim:

The ornamental design for a miniature electronic welding head, substantially as shown.

References Cited in the file of this patent

Design, No. 41, May 1952, page 9, top of page, welders items.